COMBINED TRANSPORTING AND LOWERING APPARATUS

Lewis M. Holmes, Ashland, Ohio, assignor to Ashland Vault Incorporated, Ashland, Ohio, a corporation of Ohio

Application February 24, 1939, Serial No. 258,265

1 Claim. (Cl. 254—136)

The invention relates to means for transporting and otherwise handling loads, and is particularly adaptable for the displacing and servicing of burial vaults. These vaults, being oftentimes formed of concrete, are usually comparatively heavy, weighing upwards of a ton.

The objects of the invention are to provide transporting and handling apparatus which is readily and conveniently movable both laterally and lengthwise upon suitable running gear, which is easily operated and always under the control of the operator, particularly in lifting and lowering loads, which will run smoothly over uneven ground, and which is of sturdy and durable construction. As applied to the displacing and servicing of burial vaults, the improved apparatus is of light weight so that it can be conveniently lifted and placed over the vaults; or alternatively, one form of the apparatus is adapted to be run over the vaults when the latter are on the ground or closely adjacent any other supporting surface.

Other advantages will appear in detail by reference to the following description and the accompanying drawings.

The annexed drawings and the following description set forth in detail certain means illustrating my improved transporting and lowering apparatus, such means constituting, however, only a few of the various forms in which the principle of the invention may be embodied.

In said annexed drawings:

Figure 1 is a plan view of the improved apparatus;

Figure 2 is a side elevation;

Figure 3 is an end elevation, taken from the plane indicated by the line 3—3, Figure 1;

Figure 4 is a side elevation, partly in section, upon an enlarged scale, of one corner of the improved apparatus;

Figure 5 is a fragmentary transverse vertical section, taken in the plane indicated by the line 5—5, Figure 4;

Figure 6 is a fragmentary horizontal longitudinal section, taken in the plane indicated by the line 6—6, Figure 4;

Figure 7 is a fragmentary vertical transverse section, taken in the plane indicated by the line 7—7, Figure 4;

Figure 8 is an end elevation of a modified form of apparatus, in which a certain upper cross bar has been dispensed with, and which is adapted for a vault having an end opening;

Figure 9 is an end elevation of a second modified form of apparatus having a removable lower

cross bar, and transmission-supporting corner standards of added height, this form of apparatus being adapted to travel over a vault when the latter is on the ground or closely adjacent any other supporting surface;

Figure 10 is a fragmentary longitudinal horizontal section, upon an enlarged scale, taken in the plane indicated by the line 10—10, Figure 9;

Figure 11 is a fragmentary end elevation of a modified form of apparatus in which the corner transmission-supporting standards are in axial alignment with the spindles of the casters of the running gear;

Figure 12 is a fragmentary horizontal longitudinal section, taken in the plane indicated by the line 12—12, Figure 11; and

Figure 13 is a fragmentary vertical section, taken axially of the caster spindle and in the plane indicated by the line 13—13, Figure 12.

Referring to the annexed drawings in which the improved apparatus is illustrated as applied to the displacing and servicing of burial vaults, and in which drawings the same parts are designated by the same respective numbers in the several views, and first particularly referring to that form of the improved apparatus which is shown in Figures 1—7, the apparatus has a chassis comprising a suitable carriage frame and running gear therefor which is offset from the carriage frame. Included in the carriage are end angles 1 and side angles 2, Figures 1, 2, and 3, secured together at their abutting corner ends by angle brackets 3, Figure 6. These brackets 3 have central offset tubular portions 4 forming housings

35 for the spindles 6 of caster frames 5 of yoke formation and provided with rubber tired casters or wheels 7. The upper and lower ends of the spindle housings 4 are laterally enlarged, Figure 7, and form chambers respectively for annular ball bearings 9 and combined annular and thrust ball bearings 9' between spindles 6 and such enlarged housing ends. The tops of the housings 4 are enclosed by caps 8 removably secured to the tops of the spindles 6. There are clearance areas 8 between the tops and bottoms, respectively, of the housings 4 and the bottom surfaces of the caps 8 and the top surfaces of the caster frames 5, respectively. It is thus apparent that the chassis is provided with running gear having wheels offset from its carriage frame and the casters 5 of which are adapted to support the chassis and to swivel, as required, to permit the chassis readily to be moved in any desired direction for proper alignment over a grave

40 45 50 55 52, Figure 3.

Mounted upon the chassis are upstanding corner supporting members, shown as tubular cylindrical standards 11, Figures 5 and 6, which are bolted to base blocks 12 disposed interiorly of the standards 11 and resting upon the abutting corner portions of the carriage angles 1 and 2, these base blocks 12 being in turn bolted to said abutting corner portions of the angles 1 and 2. Mounted upon the tops of the tubular standards 11 are gear housings 13. These housings 13 are formed with lower downwardly-extended flanges 13² into which the tops of the standards 11 extend and to which they are bolted, Figure 4. The gear housings 13 are formed with heads 13³ removably secured thereto.

A shaft 15 is extended transversely across one end of the apparatus, above the standards 11, and is mounted at its ends upon ball bearings in a pair of laterally-opposed gear housings 13. This shaft 15 is provided with worms 16 secured thereto within the gear housings 13. The threads of the worms 16 are either right or left hand depending on the direction of rotation required of certain parts to be hereinafter described. The intermediate portion of the worm shaft 15 is housed in one of two end tubular braces 15¹ mounted at their ends in the inner walls of the laterally-opposed gear housings 13. The ends of the worm shaft 15 extend outwardly from the gear housings 13 and are formed with crank-engaging portions 15² adapted to be actuated by a crank 23. Engaging the respective worms 16 within the said pair of housings 13 are worm wheels 17, Figures 4 and 5, secured to longitudinally extending stub shafts 18 mounted upon ball bearings in the housings 13 and extended at one end through and inwardly thereof. The stub shafts 18 are secured to the hubs of the worm wheels 17 by means of cooperating keys and open ended keyways. The inner extended ends of the stub shafts 18 are fastened by pins 35 to annular collars or plugs 24 and the latter are secured by screws 24¹ to longitudinally extending tubular shafts 14 mounted each at one of their ends upon collars 24 adjacent the said pair of housings 13 and secured at their other ends, respectively, to stub shafts notably mounted in the pair of housings 13 at the opposite end of the apparatus.

Also secured to the tubular shafts 14 by screws 24¹ and surrounding said shafts 14 are sleeves 20, one adjacent each end of each shaft 14, these sleeves 20 being formed with drum portions 21 which in turn are formed with helical cable grooves 21¹ forming runways for cables 19 having hooks 22 at one end and secured at their other ends to the drums 21, Figure 4.

It is evident from the foregoing description that actuation of a crank 23 will effect, through the worm shaft 15, worms 16, worm wheels 17, stub shafts 18, collars 24, shafts 14, and sleeves 20, the winding and unwinding of the cables 19 and hence the raising or lowering of the hooks 22. As will be understood, the worms 16 are of the self-locking type so that the load will under no circumstances cause the worms to rotate, thus subjecting the control of the load at all times to the action of the operator. In the application of the invention herein shown, these hooks 22 are adapted to engage the side handles or hooks 33 of a grave vault 32 disposed within the compass of the mechanism and displace the vault as required, the apparatus being particularly useful for lowering such a vault 32 into a grave 52, Figure 3.

I provide improved means for insuring the proper running of the cables 19 in the grooves 21¹ and the holding of the coils of the cables in proper position in said grooves. These means comprise brackets 25 secured to the inner side surfaces and adjacent the bottom of the tubular corner standards 11, Figure 4, and forming supports for upright posts 26. Also mounted at their lower ends upon the brackets 25 and encircling the posts 26 are compression springs 28. Resting upon the top of the springs 28 and slidably at one end upon the posts 26 are elongated longitudinal arms 27 whose other ends pass through enlarged holes 34¹ formed adjacent the top of upstanding pipes 34 welded at their bottom ends to the longitudinal carriage angles 2 and welded at their top ends to bearing elements 34² supported on the outer surfaces of the tubular shafts 14. The maximum lift of the outer ends of the arms 27 by the springs 28 is determined by stop pins 29 intersecting the posts 26 adjacent the tops of the latter. Means for aiding the positioning of the arms 27 in the enlarged post holes 34¹ are provided by pins 27¹ intersecting the arms 27 longitudinally adjacent the pipes 34. Surrounding the arms 27 adjacent exteriorly of the pipes 34 and mounted on said arms 27 on ball bearings are rollers 30 disposed adjacently below the cable grooves 21¹. The heights of the enlarged holes 34¹ and the pins 29 are such that the rollers 30 are caused to engage whatever turns of the cables 19 are wound on the drums 21, under the tension exerted by the springs 28. The tendency of the springs 28 is, of course, to lift the outer ends of the arms 27 so that whatever amounts of cables 19 are wound upon the drums 21 the coils thereof are held to their respective positions in the grooves 21¹ and thus a proper feeding of the cables 19 to and from said grooves 21¹ and a holding of the coils of the cables 19 to their respective positions are effected by the restraint placed thereon by the resiliently mounted rollers 30. The provision of this cable guiding mechanism is particularly essential because of the relatively small diameter of drums upon which the cables are wound and is especially necessary when the unloaded cables are wound when the cables would tend to spring away from the drums and the coils would tend to overlap.

The use of the described apparatus will be readily understood. Wherever the load, such as a grave vault, is located, the apparatus is lifted and positioned over the vault, the dimensions of the apparatus being such, as clearly shown in Figures 1, 2 and 3, that it extends beyond the ends and sides of the vault. The hooks 22 of the cables 19 are then fastened to the vault handles 33 and, after the vault is raised, it is transported over the ground by the apparatus, the latter acting as a truck, the character of the wheels 7 and the swivel mounting thereof permitting the truck with its load to be moved in any desired direction and over any character of ground ordinarily found in a cemetery. The apparatus with its vault load is run into position over the grave, as shown in Figure 3, planks 53, or other suitable supports, being disposed adjacently laterally of the two sides of the grave 52 onto which the truck is run, and upon which it is supported, during the vault-lowering operation.

Different characters of service for which the improved apparatus is designed, or different heights of vaults, require variation in the height

of the mounting of the transmission and the cable drums over the carriage level, and this desired variation is easily accommodated by using tubular corner standards 11 of a length suitable for the required service.

The apparatus heretofore described presupposes its use with a vault having a top cover member. Oftentimes grave vaults have end openings through which access is obtained for the positioning of the coffin in the vault. For use in servicing such a vault 32', Figure 8, when mounted upon the improved apparatus, the tubular brace 15' at one end of the apparatus is dispensed with and the carriage is strengthened by short inclined braces 37 secured at this apparatus end to the end angle 1' and to the gear housings 13'. The end opening for such vault is indicated by the character 32² and, it will be noted, that free access to this opening is afforded.

Oftentimes it is desirable to run the apparatus over a vault, instead of lifting the same there-over, and a modified form of apparatus for this purpose is shown in Figures 9 and 10. The necessary changes to effect the desired difference in structure are readily provided for by using corner standards 39 of the necessary greater length and substituting for the end carriage angle at one end of the machine a removable cross bar 40, and using shortened carriage frame and angle brackets 41. It is evident, as shown in Figures 9 and 10, that the bar 40 being removed and the corner standards 39 being of sufficient length, the apparatus can be rolled over and laterally by the vault 32 and properly positioned for lifting and lowering of the vault.

In one form of the improved apparatus, the corner standards for supporting the transmission and load-lowering members are axially aligned with the spindles of the casters of the running gear. Such modified form of the structure is shown in Figures 11, 12 and 13. In this form of structure the axial lines of the spindles 56 of the offset running gear yokes 55 are followed, and the offset housings 45 of the carriage frame connecting angle brackets 44 are straight cylindrical tubular members receiving

the corner standards 46 which extend to the bottom of said housings 45 and are bolted thereto and also to interior sleeves or spacers 47. Ball bearings 49 and 49' are disposed in the corner standards 46 between the standard bodies and the ends of the caster spindles 56, adjacently above and below the sleeves 47. Caps 48 for the tops of the spindles 56 are bolted to the latter and lap over upon the upper ball bearings 49.

10 What I claim is:

Load-servicing means comprising a mobile support, upstanding corner standards mounted thereon, enclosed housings secured to and 15 mounted on the respective standards, a cross-shaft whose ends intersect and are rotatably mounted in a laterally-opposed pair of said housings, a pair of longitudinally-extended shafts, stub shafts mounted in the respective housings and extended inwardly thereof, annular collars 20 secured to the respective inwardly-extended ends of the stub shafts mounted in said laterally-opposed pair of housings, sleeves mounted respectively upon the ends of said longitudinally-extended shafts, means rotatably securing together 25 said sleeves and the adjacent ends of said longitudinally-extended shafts and said collars, means respectively rotatably securing together the opposite ends of said longitudinally-extended shafts and the adjacent stub shafts, worm-wheels 30 disposed in said laterally-opposed pair of housings and secured respectively to the stub shafts of said housings, worms in said laterally-opposed pair of housings secured to the respective ends 35 of said cross-shaft and engaging said worm-wheels, respectively, means for turning said cross-shaft, said sleeves being formed with integral drum portions having cable runways, and cables 40 respectively secured at one end to said drum portions and disposed in said runways and having grab hooks at their opposite ends, each drum portion and its associated cable being a separate entity independent of the other drum portions and cables.

45 LEWIS M. HOLMES.
